United States Patent Office

Des. 224,255
Patented July 11, 1972

224,255

CHILD'S COASTER VEHICLE

Stanley M. Novak, Jr., Olney, Ill., assignor to
AMF Incorporated

Filed May 17, 1971, Ser. No. 144,372

Term of patent 14 years

Int. Cl. D21—01

U.S. Cl. D34—15

FIG. 1

FIG. 2

FIG. 3

FIG. 4

FIG. 5

FIG. 1 is a front perspective view of a child's coaster vehicle showing my new design;

FIG. 2 is a top plan view thereof;

FIG. 3 is a right side elevational view, the left side being identical thereto.

FIG. 4 is a front elevational view thereof; and

FIG. 5 is a rear elevational view thereof.

I claim:

The ornamental design for a child's coaster vehicle, substantially as shown and described.
